UNITED STATES PATENT OFFICE

RALPH R. HERRICK, OF PITTSBURGH, PENNSYLVANIA, ASSIGNOR TO UNIVERSAL OIL PRODUCTS COMPANY, OF CHICAGO, ILLINOIS, A CORPORATION OF SOUTH DAKOTA

EXPANSION DRUM

Application filed October 29, 1926. Serial No. 144,975.

The present improvements relate more particularly to a reaction drum or expansion chamber forming part of a tube and drum type of apparatus for the cracking of hydrocarbons under heat and superatmospheric pressure.

More specifically, the present invention is directed to the idea of providing an expansion drum having walls of materially greater thickness adjacent one end relative to the thickness of the walls adjacent the other end, for the purpose of balancing to a certain degree the corrosive effect of compounds produced in the reaction.

15 The walls of materially greater thickness will be provided where the corrosion is found to be most active, which in one type of tube and drum apparatus comprises the upper part of the reaction chamber. The use of an expansion drum constructed in accordance with the present invention, would obviate the necessity of discarding expansion chambers when corrosion has reduced the thickness of the walls, thus materially prolonging the life and time of use of such drums. Furthermore, the present invention enables the operator to have a thick wall where it is required from the standpoint of corrosion, and to reduce this wall thickness at the other end of the vessel where corrosion is negligible. In this manner a drum is provided which is much lighter than it otherwise would be if made of the full thickness for its entire length.

20 Various objects and advantages in addition to the above, will be hereinafter more particularly brought out.

In the drawings, Fig. 1 is a sectional view of an expansion chamber built in accordance with the present invention.

25 Fig. 2 is an enlarged fragmentary cross sectional view of one wall.

Referring more in detail to the drawings, 1 may designate a suitable support and 2 may designate angle irons or other analogous supporting elements for supporting the reaction drum, or expansion chamber designated as a whole 3. This chamber 3 may have a diameter of from three to ten feet 30 more or less, and may have a height from five

to forty feet more or less. The drum itself may be constructed in any approved manner, and it is to be understood that the present invention is not limited to the particular style, shape or method of assembling the chamber. Further, I have designated a chamber vertically disposed. It is to be understood that the present invention may be utilized with chambers adapted to be disposed in horizontal planes.

35 This chamber may be provided with the cleanout openings 4 closed by the removable doors 5, and the chamber in use may be externally unheated but insulated as shown at 6, if desired. Heated hydrocarbons which may have been heated in a tube still, may be introduced through the transfer line 7 controlled by valve 8 discharging into the interior of the chamber 3 where separation of vapors takes place. These vapors may pass out through vapor outlet pipe 9 controlled by the valve 10. Unvaporized residue may be withdrawn through any of the outlets 11, a suitable valve 12 being manipulated for this purpose.

40 In cracking heavy hydrocarbon oils of relatively low gravity containing sulphur, such for instance, as a California oil under conversion conditions of temperature and superatmospheric pressure, it has been found that compounds are formed as a result of the reaction which attack the metal walls of the chamber, eating into said wall, and eventually reducing its thickness to the point where it must be replaced.

45 It has been further found that this corrosive action is more pronounced in the vapor space of the reaction drum than in the non-vapor space. The discarding of drums in which the wall thickness has been reduced and the replacement of such drums, involves expense in material and labor.

The present invention purposed to balance the corrosive effect by varying the thickness of the walls so that the walls adjacent the upper part of the chamber will be of materially greater thickness than the walls adjacent the lower end, it being understood that the vapor space of such chamber is adjacent the upper end. This is shown dia-

grammatically in the drawings, the thickness of the wall at the point marked A being materially greater than the thickness of the wall at the point marked B.

5 One method of constructing a drum of this character, particularly where it has substantial height, is to first make tubular sections designated (Fig. 2) as 13, 14 and 15, which sections may be connected by means of electric welding, the welding material being illustrated diagrammatically at 16. The thickness of the wall in the section 15 may be, for instance, two inches. The thickness of the wall 14 may taper from two inches at its base, to say four inches at its upper end, the thickness of the wall in the section 13 10 may be say, four inches.

15 It is to be understood that these figures are merely illustrative, and any relative thicknesses may be used, which are found most suitable.

20 Although I have described a drum made up of sections connected by electric welding, it is to be understood of course, that the invention embraces drums made up in any manner, particularly including those in which the sections are connected by rivets or the like. Further, the annular edges instead of abutting 25 as shown, may overlap.

25 Although I have illustrated the inside wall of the tank as lying in a straight line, with the taper on the outside of the tank, it is to be understood that I do not wish to be limited in this way, as the taper may be on 30 the inside of the tank, or partly in the inside, and partly on the outside, as desired.

35 I claim as my invention:

40 1. A chamber for use with apparatus for cracking hydrocarbons, comprising a metal shell made up of connected sections, and having closed end and side walls, inlets and outlets associated with said walls, the section or sections adjacent one end of said shell having a materially greater wall thickness than the section or sections adjacent the opposite end.

45 2. A chamber for use with apparatus for cracking hydrocarbons, comprising a metal shell having closed end and side walls, inlets and outlets associated with said walls, the thickness of said walls being materially greater adjacent the upper end of said shell relative to the thickness of said walls adjacent the lower end.

50 3. An expansion drum forming part of a tube and drum type of oil cracking apparatus adapted to withstand cracking temperatures and pressures comprising an integral base member comprising a flanged cleaning 55 manhole with a removable cover, and a residuum draw off outlet, an integral top member of greater thickness than said base member and having a flanged cleaning manhole with a removable cover, a mixture inlet and 60 a vapor outlet and a plurality of aligned

cylindrical sections of intermediate thickness interposed between said base member and said top member, and means for securing said members and sections together to form a pressure tight shell.

65 4. An expansion drum forming part of a tube and drum type of oil cracking apparatus adapted to withstand cracking temperature and pressures comprising an integral base member comprising a flanged cleaning 70 manhole with a removable cover, and a residuum draw off outlet, an integral top member of greater thickness than said base member, and having a flanged cleaning manhole with a removable cover, a mixture inlet and 75 a vapor outlet and a plurality of aligned cylindrical sections of intermediate thickness interposed between said base member and said top member, and means for securing said members and sections together to form a pressure tight shell, said securing means comprising 80 seams of electric welding encircling said shell at the joints.

85 5. A reaction chamber for hydrocarbon oil cracking apparatus, comprising a cap member, substantially four inches in thickness, a base member of materially less thickness than said cap member, sections interposed between said cap member and said base member, and means for securing said members and sections together to form a pressure tight shell, means for admitting cracked liquid oil to said shell, and means for drawing off 90 vapors therefrom.

95 6. A reaction chamber for hydrocarbon oil cracking apparatus, comprising a cap portion having an integral flanged cleaning manhole with a pressure tight removable cover, a valved cracked mixture inlet and a valved vapor outlet, a base portion having a similar cleaning manhole, and an integral residuum draw off outlet, said base portion being of materially less thickness than the cap portion, an intermediate cylindrical portion between said cap and base portions forming 100 a pressure tight shell.

105 7. A reaction chamber for hydrocarbon oil cracking apparatus, comprising a cap portion, a base portion of materially less thickness than said cap portion and an intermediate portion, said portions forming a pressure tight shell.

110 8. A reaction chamber for hydrocarbon oil cracking apparatus, comprising a cap portion, a base portion of materially less thickness than said cap portion and an intermediate portion, said portions forming a pressure tight shell, means for admitting cracked mixture to said shell, and means for taking off vapors from said shell.

115 9. A reaction chamber for hydrocarbon oil cracking apparatus, comprising a cap portion, a base portion of materially less thickness than said cap portion and an intermediate portion, said portions forming a pressure 120 tight shell.

sure tight shell, means for admitting cracked mixture to said shell, means for taking off vapors from said shell, and an integral flanged cleaning manhole formed in one of said portions and provided with a removable pressure tight cover.

10. An expansion drum for use in oil cracking systems comprising a pressure-tight shell of greater thickness at its upper portion than at its lower portion.

11. An expansion drum for use in oil cracking systems comprising a pressure-tight shell of greater thickness at its upper portion than at its lower portion, and tapering gradually from said upper portion toward said lower portion.
